FOLDING TABLE LEG

Elinor H. Mayer, Sarasota, Fla.

Application September 3, 1943, Serial No. 501,083

9 Claims. (Cl. 311—98)

My invention relates to what are commonly called "folding tables" i. e. tables having legs which are so connected to the top frame that they can be folded compactly against the top in one position for storage and shipment and readily unfolded or spread to another position so that the table can be supported on its feet.

The main object is to provide a hinged type of connection with a latch which securely holds the leg in both positions and yet permits the leg to be readily moved from either position to the other.

Another object is to provide a form of connection which can be easily made and assembled.

Another object is to provide a form of hinged connection which is simple but sturdy and capable of withstanding rough treatment without damage.

Another object is to provide a construction which places a minimum strain upon the table top.

Another object is to provide a construction which can be readily applied to conventional table top frames.

The preferred form of the device includes (a) a bracket which affords a hinge support for the leg and a hinge support for (b) a swinging link which connects the leg to the bracket, (c) a spring pressed latch hinged to the leg and adapted to interlock with the link and (d) a stop plate carried by the leg and abutting against the bracket when the leg is extended. The bracket is adapted to be secured within the frame of the table top so that the leg when folded up lies alongside of one side of the frame beneath the top. The base of the latch and the stop plate may be formed of a single piece of metal.

Fig. 1 is a vertical sectional view of a fragment of a table top and showing a side view of a leg connected to the frame and extended in the position for use.

Fig. 2 is a similar view taken looking toward the right side of the leg of Fig. 1.

Fig. 3 is a view similar to Fig. 1 but with the leg folded up for storage.

Fig. 4 is a view taken looking upwardly at the bracket and leg of Fig. 3 and showing part of the frame in dotted lines.

Fig. 5 is a transverse sectional view on the plane of the line 5—5 of Fig. 3.

Figs. 6 and 7 are perspective views of the latch and its support, respectively.

The bracket 10 is formed of sheet metal and adapted to be secured by screws 11, 11' to the frame 12 beneath the top 13.

The wooden leg 14 has a hinge plate 15 secured to it by screws 16 and hinged to the pin 17. The hinge or loop portion of said plate is preferably located at the end of the leg thereby affording additional support for the plate.

A link or locking bar 18 is hinged at 19 to an extension lug 20 at a lower corner of the bracket. The other end of the link 18 has a slot 21 in which slides a pin or screw 22 carried by the leg 14.

The latch 23 is hinged to a plate 24 which is secured to the leg by one or more screws 25. This latch is pressed by springs 26 toward the link 18 and has a projecting lug 27 adapted to engage and hold the link 18. In the folded position this lug extends into the slot 21 as shown in Fig. 3 and in the extended position it projects alongside the link as shown in Fig. 1 to hold the leg extended.

The latch has a suitable finger piece 28 by which it may be actuated to release the lug from the link. A spring 29 may be secured to the leg in position to engage the underside of the table top so as to tend to force the leg toward the extended position when the latch is released.

The plate 30 secured to the leg by screws 31 has lugs or shoulders 32 adapted to abut against the lower end 33 of the bracket when the leg is fully extended.

It will be noted that the stress applied to the lug 27 when attempt is made to extend it from the position of Fig. 3 to that of Fig. 1 is in a direction longitudinal of the link 18 and edge-wise to the lug 27 and the latch 23. I therefore prefer to provide flanges 34 to reinforce the plate 24 and support the latch. It will also be noted that the stress applied to the lug 27 when attempting to fold the leg from the position of Fig. 1 to that of Fig. 3 is in a direction at substantially right angles to that above mentioned. Actually the two functions are performed by two different parts of the lug 27. In fact there might be two separate lugs, one to hold the leg folded and the other to hold the leg extended.

The hinge plate 15 and a portion of the supporting plate 30 are shaped to fit between the spaced side walls of the bracket 10 when the leg is in extended position; that is, the side edges of the plate 15 slidably engage and contact the inner surfaces of the bracket walls as viewed in Fig. 2, and the side edges of the portion of plate 30 above the lugs 32 slidably engage the inner surfaces of said bracket walls adjacent the bottom thereof and are in contact with the corners of 55 said bracket walls when in operative position.

By reason of this construction, a rigid metal-to-metal support is afforded, and at the same time jamming of the wooden leg between the bracket walls caused by expansion of the wood is prevented.

I claim:

1. A table leg hinge construction comprising a socket type bracket for attachment to the top frame of the table, a leg hinged to the bracket, a locking bar hinged to the bracket and having a pin and slot sliding connection with the leg, and a latch hinged to the leg and having projecting means interlocking with the locking bar in the folded position of the leg and in its extended position.

2. A table leg hinge construction comprising a socket type bracket for attachment to the top frame of the table, a leg hinged to the bracket, a locking bar hinged to the bracket and having a pin and slot sliding connection with the leg, a latch hinged to the leg and having projecting means interlocking with the locking bar in the folded position of the leg and in its extended position and separate spring means for pressing the latch against the locking bar.

3. A table leg hinge construction comprising a socket type bracket for attachment to the top frame of the table, a leg hinged to the bracket, a locking bar hinged to the bracket and having a sliding connection with the leg, a latch hinged to the leg and having projecting means interlocking with the locking bar in the folded position and in the extended position and a stop plate carried by the leg abutting against the bracket in the extended position of the leg.

4. A table leg hinge construction comprising a bracket for attachment to the top frame of the table, said bracket having spaced parallel walls forming a socket, a leg hinged to the bracket, a locking bar hinged to the bracket and extending along the leg and having a pin and slot sliding connection with the leg, a support secured to the leg, a latch hinged to the support and having projecting means interlocking with the locking bar in the folded position and in the extended position and a stop carried by the support abutting against the bracket when the leg is extended.

5. A table leg hinge construction comprising a bracket for attachment to the top frame of the table, said bracket having spaced parallel walls forming a socket, a leg hinged to the bracket, a locking bar hinged to the bracket and extending along the leg and having a pin and slot sliding connection with the leg and a latch hinged to the leg and carrying a single lug interlocking with the locking bar in the folded position of the leg and in its extended position.

6. A table comprising a top, a plurality of legs for supporting said top, a hinge connection between each leg and the top including a bracket secured to the top, a hinge plate secured to the leg and hingedly connected to bracket adjacent

the top and means for holding the leg in upright and folded positions consisting of a locking bar hingedly secured at one end to the bracket and slidably secured at its other end to the leg and a spring pressed latch adapted to engage said locking bar in both positions of the leg.

7. A table comprising a top, a plurality of legs for supporting said top, a hinge connection between each leg and the top including a bracket secured to the top, a hinge plate secured to the leg and hingedly connected to the bracket adjacent said top and means for holding the leg in upright and folded positions consisting of a locking bar hingedly secured at one end to the bracket and slidably secured at its other end to the leg, a spring pressed latch adapted to engage said locking bar in both positions of the leg and a finger piece on the latch positioned underneath and adjacent the top when the leg is in upright position for releasing the holding mechanism.

8. A table comprising a top, a plurality of legs for supporting said top, a hinge connection between each leg and the top including a bracket secured to the top, a hinge plate secured to the leg and hingedly connected to the bracket adjacent said top and means for holding the leg in upright and folded positions consisting of a locking bar extending along said leg and hingedly secured at one end to the bracket and slidably secured at its other end to the leg, a spring pressed latch having a lug adapted to engage said locking bar in both positions of the leg, a finger piece on the latch positioned adjacent the top when the leg is in upright position for releasing the holding means and a separate spring between the leg and top for facilitating movement of the leg upon release of the latch.

9. A table having a downwardly extending frame portion forming corners, a bracket fastened to said frame portion within the confines thereof at each corner and provided with spaced parallel walls forming a socket portion, a leg member hinged to said bracket and having its hinge line positioned within said socket portion, a pin carried by said leg, a plate fastened to said leg member adjacent the lower edge of said frame portion when the leg is in extended position, a latching plate positioned over and hinged to said first-named plate, a projecting lug on said latching plate, a finger piece on said latching plate and forming an extension thereof and being positioned adjacent the lower edge of the frame portion when the leg is in extended position, a locking bar hinged at one end to said bracket and having a slot slidably connected to the pin on said leg, said locking bar and hinged latch being so positioned relatively that the projecting lug on said latch engages the edge of said bar when the leg is in extended position and engages the wall of the slot of the bar when the leg is in folded position thereby holding said leg in such moved positions.

ELINOR H. MAYER.
